METHOD OF AND APPARATUS FOR INCREASING THE VOLUME OF MECHANICALLY-
REPRODUCED SOUNDS

Application filed January 23, 1925, Serial No. 4,180, and in Germany February 2, 1924.

My invention has reference to sound-reproducing machines and more particularly to phonographs, gramophones, and the like. The object of my invention is to increase the 5 volume of the sound produced by the reproducing means, and my invention consists in a novel method of accomplishing this object.

I have found that if two or more sound reproducing means are employed and during 10 the reproduction a certain time interval is maintained between the reproduction of the sound by the first sound reproducing means and the reproduction of the sound by the other sound reproducing means, the quality 15 of the sound thus reproduced is considerably improved and the sound thereby more nearly approaches the natural sound either of the human voice, music instrument or the like, being reproduced. I have found that with 20 a time interval of from about one sixth (1/6) to one fortieth (1/40) of a second between the first sound reproducing means and the other sound reproducing means a prolongation 25 of the sound reproduced is obtained which imparts to the sound the character or quality of the natural sound, i. e. the sound which is being reproduced. The best results are obtained with a time interval of from one tenth (1/10) to one twentieth (1/20) of a 30 second when used on phonographs and similar recording instruments in which disks are employed carried by a rotatable support.

For a better illustration of my invention, I refer to the accompanying drawing, showing 35 in plan view a phonograph equipped with two separate tone arms each carrying the usual sound box.

As seen in the drawing, the tone-arms 3, 4 are disposed on the same side of the rotatable 40 disk support 1, which is mounted on the spindle 2. The tone-arms lead to the horn connections, indicated respectively at 5 and 6. The tone-arm 4 is shorter than the tone-arm 3 so that the sound transmitted through the 45 former tone-arm does not have to travel very far to reach the horn. The elbow 9 at the free end of the tone-arm 3 carrying the sound box 7 and stylus 11 forms with the tone-arm an acute angle, whereas, the elbow 10 of the 50 shorter tone-arm 4 carrying the sound-box

8 and stylus 12 is substantially at a right angle to its tone-arm.

In the starting position of the two tone-arms, the actual distance between stylus 11 and stylus 12 is about 9 centimeters, while at 55 the finish, i. e. the position indicated by the broken lines, the distance between the two styluses is 4.5 centimeters. Because of this arrangement, a time interval of about one fifteenth (1/15) of a second is maintained 60 between the sounds produced by the two sound boxes or styluses as they move across the record, which time interval gives excellent results. At a uniform rotation of the rotatable support 1, the two styluses travel, during 65 a given time, almost twice as far along the outermost groove in the record than along the innermost groove. Therefore the distance between the two styluses 11 and 12 is gradually reduced from 9 centimeters at the 70 starting point to 4.5 centimeters at the finish. Because there would otherwise be a more prolonged reproduction of the sound at the finish than at the start, which would disturb the 75 uniformity in the sound reproduction.

To insure a uniform rotary movement of the sound record I prefer to provide the driving means at the circumference of the disk 1, said driving means being in the form of a roller 13 of rubber or the like frictionally 80 engaging the edge of the disk and forming a part of a suitable driving mechanism not shown. I have found that where two tone-arms 3 and 4 are used engaging the sound record, a central driving means such as ordinarily provided is not sufficient to overcome the increased resistance of the disk. Moreover the roller 13 engaging the edge of 85 the disk 2 steadies the movement of the disk by preventing oscillations in vertical direction caused by the weight of the tone arms 3 and 4 bearing on the record disk on one side thereof.

The underlying principle of my invention consists in a double or multiple reproduction 90 of the sound by the same recording means with a suitable time interval between the sounds as reproduced by the first sound reproducing means and the sounds reproduced by the other sound reproducing means 95 100

While in describing the invention I have made reference to a particular embodiment of the same, I wish it to be understood that my invention is of course not limited to the construction shown in the drawing, since various changes may be made in the general arrangement of the apparatus and the construction of its parts without a departure from the essence of invention.

10 I claim:

1. In a sound reproducing machine, means for supporting and rotating a grooved sound record, a pair of sound reproducing devices for cooperation with one another to reproduce the same sound in the same location at time intervals indistinguishable to the normal ear, each of said devices being inclusive of a stylus, and means mounting said devices so that said styli are disposed in spaced relation to one another and adapted to track tandem in the groove of said record, the distance between said styli approximating the angular distance traveled by any point in said record during rotation thereof at a normal rate of speed and during a time interval of from one-fortieth to one-sixth part of a second.
2. In a sound reproducing machine, means for supporting and rotating a sound record of the disk type having a spiral record groove, a pair of sound reproducing devices for cooperating with one another to reproduce the same sound in the same location at time intervals indistinguishable by the normal ear, each of said devices being inclusive of a stylus, and means mounting said devices so that said styli are disposed in spaced relation to one another and adapted to track tandem in the groove of said record and in converging arcs towards the center of the record, the distance between said styli at all times approximating the angular distance traveled by any point in said record during rotation thereof at a normal rate of speed and during a time interval of from one-fortieth to one-sixth part of a second.

In testimony whereof I affix my signature.

HEINRICH KÜCHENMEISTER.
